INTERPRETER CARD FEED

Arnold B. Crowell, Endicott, N. Y., assignor to
International Business Machines Corporation,
New York, N. Y., a corporation of New York

Original application August 13, 1947, Serial No.
768,373. Divided and this application August
12, 1949, Serial No. 109,996

8 Claims. (Cl. 101—93)

1

This invention relates to an interpreter and its principal object is to provide a machine of this type with improved line selecting means.

The present application is a division of my pending application, Serial No. 768,373, filed August 13, 1947, and is related to another divisional application, Serial No. 109,995.

The type of machine with which the invention is concerned is one which feeds record cards and reads the data recorded in them by sensible indicia, such as punched holes, and prints an interpretation of the data back on the card. Card designs vary and in some cases it is desirable to print an interpretation on one line and in some cases on another, or it may be necessary to print a plurality of interpretations of data from different fields on different lines of the card.

Accordingly, it is a particular object of the invention to provide an interpreter having great flexibility in respect to the line position on which the interpretation is to be printed.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a side elevation of an interpreter embodying the invention.

Fig. 2 is a vertical section of the card feed unit, looking in the opposite direction to Fig. 1.

Fig. 3 is a detail view of a part of the line adjusting mechanism.

Fig. 4 is a side elevation of one part of the printing drum operating mechanism.

Fig. 5 is a side elevation of another part of the printing drum operating mechanism.

Fig. 6 is a plan view of a portion of the card feed unit, showing the printing drum end.

Fig. 7 is a timing chart of the printing drum.

Fig. 8 is a portion of a tabulating card illustrating the punching and interpretation.

Fig. 1 of the drawing shows the general arrangement of an interpreter embodying the principles of the invention. It comprises a card feed unit A at the right or front end of the machine and a printing unit B at the left or rear end. The functions of the card feed unit are to feed cards one at a time to a control station, where their control designations are analyzed; then to a reading station, where the data stored in them is read; then to a printing station, where the data is interpreted on the cards by the printing unit; and then to a stacker. The function of the printing unit is to store the data read from the cards and to print the data on the cards as they are presented in succession at the printing station.

The cards for which the illustrative machine

is designed are the standard 80 column International tabulating cards, one of which is partially shown in Fig. 8. These cards are divided into 80 vertical columns (see the small column numbers at the bottom of the card), in which data are stored by punching holes in one or more of 12 horizontal rows or index point positions. These index point positions are identified, beginning with the top, as R, X, 0, 1, 2, 3, 4, 5, 6, 7, 8, and 9. The card shown in Fig. 8 has stored in it, by perforations in columns 1 to 22, "John Smith 115 Elm St." Fig. 8 shows the card after this information stored by means of punched holes has been interpreted by the machine disclosed in the drawing. In this case the line of interpretation is the line just below the uppermost, or "R," index point position. As will be seen later, the interpretation may be placed in any index point position except the "9" position, or on a line just above any one of the index point positions. The character spacing of the interpretation is somewhat wider than the column spacing of the punched record.

The card feed unit

A stack of cards 10 is placed in a hopper 11 at the right end of the machine shown in Fig. 1, face down and with the "9" row forward, that is to the left in Fig. 1. Fig. 2 shows the card feed mechanism in vertical section as seen from the opposite side from Fig. 1. At the bottom of the card hopper is a picker mechanism, which comprises a reciprocating member 12 provided with a knife 13 projecting above the top surface of the member 12 for slightly less than the thickness of one card. The picker mechanism is reciprocated by rocker arms 14 fixed to a rock shaft 15, which has fixed at its remote end in Fig. 2 a rocking lever 16 urged in one direction by a spring 17 and moved counter-clockwise once each machine cycle by a vertically travelling pitman 18 articulated to its left end. The pitman has a cam follower roller 19 bearing upon a cam 20 fixed to the end of the main card feed shaft 21. This shaft is driven by a bevel gear 22 meshing with a bevel gear 23 fixed to a gear 24 meshing with a gear 25. The latter gear is rotatably mounted on a shaft 26 and has fixed to its hub a clutch arm 27 on the end of which is pivoted a clutch dog 28. An outwardly directed tail 29 of the dog 28 and a tip of the clutch arm 27 directly behind it are normally latched by a hook 30 controlled by the card feed clutch magnet CFCM. When this magnet is energized the hook 30 releases the clutch dog and the clutch arm and the dog is pulled by a spring 31 into engagement with a notched disc 32 fixed to a gear 33. The gear 33 is driven through gears 34, 35, and 36, by a gear 37 on a shaft 38. The shaft 38 has keyed to it a pulley 39 driven through a belt 39' by a

motor, not shown in Fig. 1. The clutch arm 27 will make one revolution and will then be latched up, by the hook 30 if the card feed clutch magnet has not been energized again. One revolution of the clutch arm causes one cycle of operation of the card feed unit.

Once in each cycle the picker knife 13 moves back to take hold of the rear edge of the lowest card in the stack and is then moved forward by the spring 17 to feed the card out of the bottom of the hopper into a pair of feed rolls 40, 41. There are three other sets of feed rolls in the card feed unit: 42, 43; 44, 45; 46, 47. The feed rolls 40, 41 and 44, 45 are purely conveying rolls, while the lower one of each pair of feed rolls 42, 43 and 46, 47 is called a contact roll and has an electrical function in addition to its conveying function. The feed rolls feed the card between card guides 48. The contact rolls 43 and 47 have a metallic surface on which bear brushes 50 and 51, through which they are electrically connected with one side of the line. On the upper side of each of the contact rolls 43 and 47 bears a set of analyzing brushes 52 and 53. There are 30 brushes in each set, one for each column of the card, and they are mounted in electrical insulation on insulating bars 54 and 55. The brushes 53 are called reading brushes, because they read the data stored by the punched holes in the card and transmit it to the storage device of the printing mechanism. The brushes 52 are called control brushes, because they are concerned with controlling the operations of the machine.

The lower feed rolls 41 and 45 are driven from the shaft 21 by pairs of bevel gears 56 and drive the contact rolls 43 and 47 through gears 57.

The printing drum

From the feed rolls 46, 47 the cards pass through the last card guides 48 to the printing drum 60. The printing drum comprises two independently operable platen members 61 and 62. The platen member 61 is shown in the position it assumes for holding the card at the printing station, opposite a row of type members 63, while the platen member 62 is shown in card receiving position. When the card held by platen member 61 has been printed upon, this platen member advances counterclockwise to the position in which platen 62 is shown in Fig. 2, leaving its card in a stacker 64 in passing. At the same time, the platen member 62 advances from the card receiving position to the printing station. In the next machine cycle a card held by platen member 62 will be printed upon and then conveyed to the stacker 64, while the platen member 61 will receive the following card from the feed rolls 46, 47.

The two platen members are generally similar in construction, but have slight differences, due to the fact that one is nested inside the other. Fig. 4 shows the platen member 62 and its actuating mechanism alone, in card receiving position, while Fig. 5 shows the platen member 61 and its actuating mechanism alone, in card printing position. Referring first to Fig. 4, the platen member comprises a cylindrical platen 66 which is supported by two side arms 67 and 68 on the shaft 65 (see also Fig. 6). The hubs of these side arms are fixed to the shaft by set screws 69. At the front edge of the platen 66 is a card clamp comprising a shaft 70 and clamp fingers 72. The shaft 70 is rockably mounted in flanges 73 of the platen and can rock sufficiently to withdraw the clamp fingers 72 from the platen surface to ac-

cept a card. Each one of the clamp fingers has associated with it a spring 74, one end of which is hooked over a pin 75 on the hub of the clamp finger, while the other is anchored on a shaft 76 which extends for the length of the platen member. These springs normally hold the card clamp shut. The shaft 70 has fixed to it a lug 77 (Fig. 2) which coacts with a stationary cam 78. This cam 78 has a hump 79 which rocks the clamp open at the card receiving station and another hump 80 which rocks it open as the card is delivered to the stacker. At all other times the clamp is closed. Two clips 81 serve as card stops when the platen member is in card receiving position. A lug 82 with a V-notch 83 coacts with a spring detent 84 to hold the platen member in card receiving position.

The shaft 65 has pinned to it a hub 85 (Fig. 6) with a single-notched clutch flange 86. Beside the flange 86 is a hub 87 revolvably mounted on the shaft 65 and held in place by a spacer 88. The hub 87 has a clutch arm 89 on which is pivotally mounted a clutch dog 90 cooperating with the clutch flange 86 and pressed thereagainst by a spring 91. The hub also has a set of gear teeth 92 meshing with the teeth of a large sector 93 revolvably mounted on a shaft 94. The large sector is connected by a spring 95 hooked over its pin 96 to a pin 97 on a driving arm 100 rotatably mounted on shaft 94. The pin 97 extends through an opening 101 in sector 93. The large sector 93 also has a bearing stud 102 projecting through a slot 103 in driving arm 100, on which is revolvably mounted a cam 105. Against this cam bears a roller 106 mounted on a stud 107 on the driving arm 100. The large sector 93 and the driving arm 100 normally have the relative position shown in Fig. 4, but by rotating the cam 105 the large sector can be made to move to the right in relation to the driving arm. The hub of the cam 105 has a set of gear teeth 108 meshing with teeth 109 of a small sector 110 also revolvably mounted on shaft 94. The small sector has an arm 115 secured to it by screws 116 and carrying a roller 117 at its upper end which rests against a stop 118 at the particular time in the machine cycle illustrated in Fig. 4. The small sector is urged toward the right, in relation to the driving arm, by a spring 119 hooked over its pin 120 and a pin 121 on the driving arm 100. In order to move to the right the sector 110 would have to rotate the gear 108, because the supporting stud 102 of this gear is fixed to the large sector 93, which has a definite relation to the driving arm 100 established by the spring 95 and cam 105. The spring 95 is strong enough to prevent rotation of gear 108 by spring 119. The driving arm 100 has revolvably mounted on it a roller 124 riding on a cam 125. An extension 126 of the driving arm 100 carries a roller 127 bearing upon a complementary cam 128. Both of these cams are pinned to a shaft 130. A gear 131 (Fig. 5) is also pinned at its hub to the shaft 130 and meshes with a gear 132 on the shaft 133 of the lower feed roll 45. The ratio of the gears 131 and 132, is such that the cam shaft 130 turns one revolution in two machine cycles.

In operative relation to the roller 117 is a cam 135 pinned to a shaft 136. This shaft has secured to it a gear 137 (Fig. 3) meshing with a gear 138 fixed to a shaft 139. The shaft 139 has a hand knob 140 bearing graduations, which move in relation to an index mark 141 to indicate the line of the card on which the interpretation will be printed. The movement of the cam 135 is limited

by an arm 142 on gear 137, in the path of which are two stops 143. The manner in which the printing line is determined by this mechanism will be described presently.

The alternate platen mechanism 61 differs from the one first described in a number of respects, which will now be pointed out, with reference to Figs. 2, 5, and 6. A cylindrical platen 66' has two supporting arms 67' and 68' by which it is mounted on the shaft 65, these arms lying outside of the arms 67 and 68 of the platen member 62 and being revolvably mounted on the shaft 65. The card clamp 70', 72', 74', 75', 77', is substantially identical to that of the platen mechanism 62, the operating lug 77' being controlled by the same stationary cam 78. The arm 67' has fixed to it a flange 145 on a tube 146 revolvably mounted on shaft 65, which extends out to a terminal single-notch clutch flange 86'. Revolvably mounted on the shaft 65 beside the clutch flange 86' is a hub 87' having a clutch arm 89' pivotally supporting a spring operated clutch dog 90'. On the hub 87' is a gear 92' meshing with a large sector 93'. The operating mechanism for this platen member is the same as the one first described and is identified in the drawing by similar reference numerals with prime marks. The only difference is that the main driving cam 125' and complementary cam 128' are angularly displaced, in relation to the corresponding cams 125 and 128 by 180°. The line adjusting cam 135' is mounted on shaft 136 at the same angle as cam 135.

The operation of the printing drum will now be described, by referring to the platen member 62 and its operating mechanism, which are shown in Fig. 4 at 321.75° machine time, and to the card feed timing chart, Fig. 7. The cam follower 124 is at the low part of the cam 125 at this time. The platen member stands in card receiving position and the card clamp is open. The lug 77 is just on the edge of the hump 79 of cam 78, so that the slightest forward movement of the platen member will cause it to drop off the stationary cam and clamp the bottom edge of the card. The platen member 62 is detented in card receiving position by detent spring 84 engaging a notch 83. The knob 140 is set to print on the lowest printing line, midway between the "8" and "9" index point positions.

When the cam 125 turns counterclockwise the driving arm 100 swings to the right. The roller 106 pushing against the cam 105 moves the large sector 93 to the right and rotates the platen member 62 in counterclockwise direction. The card clamp engages the card as soon as this movement begins and as the cam 125 turns to 72° of the machine cycle, the card is conveyed up to the printing station (see curve 150, Fig. 7), where it is held bottom edge up, with the lowest printing line in position opposite the line of type 63. The small sector 110 follows the movement of the driving arm 100 and large sector 93, the roller 117 striking the surface of cam 135 just at 72°. During the next part of the machine cycle, until 308.56°, there is no further movement of the platen member 62, while the cam follower is travelling on the concentric portion of the cam 125. The printing takes place during this time, the type being positioned upside down, because of the inverted position of the card. The operation so far described occupies almost one machine cycle.

Further rotation of the cam 125 swings the driving arm 100 and large sector 93 further to the right and drives the platen member 62 on in

counterclockwise direction from the printing station. The platen member passes through the highest point of its revolution at 334.63°, stacks the card at 57.27°, and arrives at the card receiving station at 185.04°, the follower 124 rolling over the highest point of cam 125 at this time. The platen member is latched up by the detent 84 and the dog 90 idles back over the clutch disc 86, dropping into the notch of the disc again after completing a clockwise revolution.

Part of the motion of the platen member 62 after 308.56° is due to the action of the cam 105. As soon as the further motion of the large sector 93 begins the cam 105 begins to revolve clockwise, because the arm 115 is stopped by the line setting cam 135 and as the shaft of the gear 108 goes to the right the gear rolls on the small sector 110, turning cam 105. This drives the shaft 102 of the cam 105 away from the center of roller 106 and has the effect of making the large sector 93 move forward more rapidly than the driving arm 100. The accelerated movement of the large sector ends when the roller 106 moves onto the high concentric part of the cam 105; from then on the large sector and the driving arm move at the same rate. In the diagram, Fig. 7, the vertical distance represents circumferential travel of the platen member, the direction being reversed at 334.63°, the highest point in the path of the platen member.

Adjusting the printing line

If the cam 135 is adjusted to the position for printing above the "R" row, the roller 117 comes into contact early in the rightward movement of the driving arm 100 and the accelerated movement of the large sector 93 begins before the card reaches the printing station, as shown by the curve 151. Thus the platen member advances a greater distance before the roller 124 comes onto the concentric portion of cam 125, which occurs at the time the roller 106 rides onto the concentric portion of cam 105. The card is held in position for printing on the line above the "R" row, during the dwell in cam 125.

It will be seen that the movement of the large sector is derived from the cams 125 and 105 and its total movement is the same in all cases. The only thing that changes is the timing of the accelerated motion caused by the cam 105, which varies in dependence upon the position of the line adjusting cam 135.

The movement of the platen member 61 from the card receiving station begins at 321.75°, one cycle later than the movement of the platen member 62 from the card receiving station and at the time the latter platen member is on its way from the printing station to the stacker. The movement of the platen member 61 is shown by the curves 150' and 151'. These curves start at a lower level than the curve 150, to represent the fact that the platen member 62 has advanced some distance out of the printing position before the platen member 61 leaves the card receiving station.

In its travel with the platen sector the card is guided by cylindrical guides 152 and 153, which are separated at the printing position to enable the type to print upon the card. Leaving the guide 153 the card passes outside of two narrow card guides 154 and 155 (Fig. 6) and behind a displaceable stacker plate 156, which rides upon rollers 157 in grooves 158 of a stacker chute 159. As a card strikes the bottom of the stacker chute 159 it is stripped out of the platen, the card clamp

72 being released at this time by the engagement of the lug 77 with the knob 80 of the stationary cam 78. As the card stack builds up in the stacker the plate 156 travels up the stacker chute to accommodate the growth of the stack.

While there have been shown and described and pointed out the fundamental novel features of the invention as applied to a single modification it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In a card interpreter, a reading station, a printing station, and card feed means to feed cards through said stations in sequence, including conveying means to convey individual cards from a position beyond said reading station to said printing station, said conveying means comprising a platen and means to clamp a card thereto; means to move said platen, with a card clamped thereto, from the position in which it receives a card beyond said reading station to a position in which it holds the card for printing; and means for varying the extent of said movement to select the line of the card presented to the printing station.

2. A card interpreter as described in claim 1, wherein the means for moving said platen comprises a main driving cam, a rockable driving arm member having a follower engaging said main driving cam, a variably movable member geared to said platen, means providing a driving connection between said driving arm member and said variably movable member, comprising a bearing element on one of said members and a rotary cam element on the other of said members engaging said bearing element, and means to impart variable angular movements to said cam element during the movement of said driving arm by said main driving cam.

3. A card interpreter as described in claim 2, wherein the means to impart variable angular movements to said cam element comprises a gear fixed to said cam element, a sector having teeth meshing with said gear, spring means connecting said sector to said driving arm member, and adjustable stop means to limit the movement of said sector with said driving arm member.

4. A card interpreter as described in claim 1, wherein the means for moving said platen comprises a main driving cam, a rockable driving arm member having a follower engaging said main driving cam, a variably movable member geared to said platen, means providing a driving connection between said driving arm member and said variably movable member, comprising a bearing element on one of said members and a rotary cam element on the other of said members engaging said bearing element; said main driving cam having a rise for moving said platen to the printing station, a dwell for holding said platen stationary at the printing station, and a further rise for moving said platen beyond the printing station; and means to impart variable angular movements to said cam element during the first rise of said cam, to impart a supplementary movement to said platen for line selection.

5. A card interpreter as described in claim 1, wherein the means for moving said platen comprises a main driving cam, a rockable driving arm member having a follower engaging said main driving cam, a variably movable member geared to said platen, means providing a driving connection between said driving arm member and said variably movable member, comprising a bearing element on one of said members and a rotary cam element on the other of said members engaging said bearing element; said main driving cam having a rise for moving said platen to the printing station, a dwell for holding said platen stationary at the printing station, and a further rise for moving said platen beyond the printing station; and means to rotate said cam element, including means to variably distribute portions of said rotation, so that a variable portion occurs during the first rise of said main driving cam, for line selection, and the remainder during the second rise of said main driving cam.

6. In a card interpreter having a printing station, a plurality of nested platens comprising cylindrical segments mounted for independent orbital movements about the same axis, each having means to clamp a card thereto; driving means for each platen to advance the platen by intermittent movements first from a receiving station to said printing station and then forward to said receiving station again, the steps of movement of the different driving means being out of phase with each other, so that the platens are brought to the printing station one after another; and means for feeding cards to said platens at said receiving station.

7. In a card interpreter having a printing station and card feeding means to deliver cards to a receiving station, a platen movable from said receiving station to said printing station, means to clamp to said platen a card delivered thereto at said receiving station, a driving member having a constant stroke of movement, and connections between said driving member and said platen whereby the stroke of said driving member moves said platen from said receiving station to said printing station, said connections including means to impart a variable supplementary movement to said platen relative to said driving member, for line selection.

8. A card interpreter as described in claim 7, wherein said connections include an intermediate member yieldably connected to said driving member; an adjustable stop to limit the travel of said intermediate member; and means operated by said intermediate member when stopped, for driving said platen ahead of said driving member.
